UNITED STATES PATENT OFFICE.

JOSEPH R. SMITH, OF WATERBURY, CONNECTICUT, ASSIGNOR TO THE WATERBURY
BUTTON COMPANY, OF WATERBURY, CONNECTICUT, A CORPORATION OF CON-
NECTICUT.

SELF-WINDING DEVICE FOR EYEGLASS-CORDS AND THE LIKE.

1,120,341.

Specification of Letters Patent.

Patented Dec. 8, 1914.

Application filed April 8, 1914. Serial No. 829,402.

To all whom it may concern:

Be it known that I, JOSEPH R. SMITH, a citizen of the United States, residing at Waterbury, New Haven county, State of Connecticut, have invented certain new and useful Improvements in Self-Winding Devices for Eyeglass-Cords and the like, of which the following is a full, clear, and exact description.

10 My invention relates to a device for winding up chains or cords for eye-glasses and the like, the object of the invention being to provide a very serviceable compact and manually controllable device of the character described.

15 In the drawings I have shown a device of a construction appropriate for winding up an eye glass chain so that the eye glass may be supported from the winding device which 20 is so arranged that it can be pinned on the clothing at some convenient point.

25 In the drawings Figure 1 is a perspective view of my invention approximately full size. Fig. 2 is a relatively enlarged cross-section of the case showing some of the internal parts in plan. Fig. 3 is a section on the plane of the line 3—3, Fig. 2. Fig. 4 is a section on the plane of the line 4—4, Fig. 2. Fig. 5 is a similar view showing the 30 parts in a different position. Figs. 6, 7 and 8 are perspective views of details.

1 represents a length of chain.

2 is one section of the casing, in this case the rear section, on which is mounted a 35 suitable pin 3 or other suitable fastening whereby the holder case may be secured on the clothing.

4 is the front part of the case suitably connected with the back part 2 so as to 40 form a housing.

5 is a flanged reel having a grooved perimeter and having a central web portion 6. At one side of the web portion is a spring pocket in which is housed a coiled spring 7 45 which is anchored at one end, preferably by means of a bent in finger 2^a on the case section 2, to a central non-rotatable stud or post 8, and its other end is suitably secured to the reel 5 so that when the reel 50 5 is turned in the direction to withdraw the

chain 1 from the holder, it will tighten up on the spring 7, whereby when the chain is fully extended, the spring will assume approximately the position shown in Figs. 3 and 4. In this position, the spring is under 55 tension and naturally will rotate the reel in a direction to rewind the chain 1, the said chain entering the case through a suitable slot 9. When the chain is extended or drawn out, it is desirable to provide effective means for preventing the reel from rewinding unintentionally. To that end I provide a novel locking mechanism in the form of a manually controllable spring pawl coacting with ratchet teeth on the reel. 60 These ratchet teeth are formed on the flat side of the web 6 and are indicated at 10—10, in this particular instance four of said teeth being provided. The pawl is preferably formed from a spring plate 70 which may be made from a blank shaped approximately as shown in Fig. 8, said blank being bent into the form shown in Fig. 4 which shows its position of rest.

11 is the pawl end which engages the 75 teeth 10, the bearing or fulcrum being indicated at 12, and the trip end indicated at 14.

15—15 are spring ends. These latter ends may be secured to a plate 16 rigidly carried by the stud 8, the ends 15—15 being slipped under lugs 17—17 formed at the plate 16, which lugs are pressed down so as to bind on the ends 15—15 and hold the parts united. The bearing or fulcrum point 80 12 (Fig. 4) is located, as shown, to the rear of the retaining lugs 17, so that by pressing on the trip end 14 of the pawl element, the pawl end 11 will be lifted out of the path of the ratchet teeth 12 thus releasing the 85 reel and permitting it to be rewound by the spring 7.

18 is a button at the front face of the reel housing, the shank of the button passing through a hole in the front face of the 90 housing so that the inner end, which may be headed, will bear against the trip end of the pawl. Hence, by pressing on the button 18, the pawl 11 may be released, whereupon the reel will rewind the chain 1. 100

By this very simple and effective arrangement, I am able to make all of the parts very compact and am likewise able to provide an effective reel engaging means to hold it against rewinding until the proper time. The outer edge of the reel snugly fits within the housing, so that the chain 1 will be prevented from wedging in any space, but will be contained wholly within the chain groove of the reel when wound thereon. Obviously, the reel should be so fitted and mounted as to turn with entire freedom save as restrained by the spring 7 and pawl 11. The arms 15—15 of the pawl in operation act not only to hold the pawl in proper position, but likewise act as springs tending to move the pawl end 11 from the position shown in Fig. 5 to that shown in Fig. 4, when pressure on the button 18 is released.

It will be understood, of course, that various modifications can be made without departing from the spirit or scope of this invention and that in the drawings and specification, I have described only the preferred embodiment.

It will be observed that there is a space between the tops of the ratchet teeth and the inner surface of the outer member 4 of the casing, said space being slightly greater than the thickness of the pawl end 11, so that when the pawl end 11 is withdrawn from in front of the teeth 10—10, the reel may rewind freely under the influence of the spring 7.

In Fig. 1, I have shown the chain 1 of the type associated with a pair of eye glasses, the latter being indicated in dotted outline.

What I claim is:

40 1. In a device of the character described, a housing, a reel rotatably mounted therein, said reel including a grooved flange and also a web portion providing pockets on opposite sides thereof and within the housing, a coil spring in one of said pockets at one side of said web, said spring being anchored at one end within the housing and secured at its opposite end to the reel, a reel holding device located in the other 45 pocket and comprising a spring-actuated pawl mounted within the housing, a stop on the side face of said reel adjacent to said pawl and arranged to be engaged thereby, with manually operable means for moving the pawl out of holding engagement with said stop.

2. In a device of the character described, a housing, a reel rotatably mounted therein and having a grooved periphery, a chain 60 passage in the housing adjacent said groove, said reel having a web portion providing pockets on opposite sides thereof within said housing, a coil spring in one of said pockets at one side of said web, means within the

housing constituting a stationary abutment, 65 one end of said spring being anchored thereto, the opposite end of said spring being secured to said reel, a reel holding device comprising a spring-actuated pawl mounted within the housing and in the 70 pocket opposite the one first mentioned, ratchet teeth on the side face of said reel arranged to be engaged by said pawl, manually operable means coöperating with said pawl for moving the same out of holding 75 engagement with said reel.

3. In a device of the character described, a housing, a reel rotatably mounted therein and having a grooved perimeter, a chain passage in the housing adjacent said groove, said reel having a web portion providing pockets on opposite sides thereof within said housing, a coil spring in one of said pockets at one side of said web, means carried by the housing constituting a stationary 80 abutment, one end of said spring being secured thereto, the opposite end of said spring being secured to said reel, a reel holding device comprising a spring-actuated tilting pawl mounted within the housing at the side of the reel opposite the spring, and ratchet teeth facing laterally from the web of said reel and arranged to be engaged by said pawl, with manually 85 operable means carried by the housing and co-acting with said pawl to disengage the same from said ratchet teeth, said pawl being normally held in tooth engaging position.

4. In a device of the character described, 100 a housing, a reel rotatably mounted therein and having a grooved perimeter, a chain passage in the housing adjacent said groove, said reel having a web portion providing pockets on opposite sides thereof within said housing, a coil spring in one of said pockets at one side of said web, means carried by the housing constituting a stationary abutment, one end of said spring being secured thereto, the opposite end of said spring being secured to said reel, holding means for the reel comprising ratchet teeth projecting laterally from the web of the reel, and a pawl arranged to co-act with said teeth, said pawl including a pawl end for tooth engagement, a trip end opposite the pawl end and an intermediate fulcrum between the trip end and pawl end.

5. In a device of the character described, 110 a housing, a reel rotatably mounted therein and having a grooved perimeter, a chain passage in the housing adjacent said groove, said reel having a web portion providing pockets on opposite sides thereof within said housing, a coil spring in one of said pockets at one side of said web, means carried by the housing constituting a stationary 115 abutment, one end of said spring being se-

cured thereto, the opposite end of said spring being secured to said reel, holding means for the reel comprising ratchet teeth projecting laterally from the web of the reel, and a pawl arranged to co-act with said teeth, said pawl including a pawl end for tooth engagement, a trip end opposite the pawl end and an intermediate fulcrum between the trip end and pawl end, and also including integrally therewith a spring arm. 10
